(57) **CLAIM**

The ornamental design for a sport foot placement training system, as shown and described.

DESCRIPTION

FIG. 1 is a top perspective view of a sport foot placement training system showing my new design;

FIG. 2 is a bottom perspective view thereof;

FIG. 3 is a top perspective view thereof, along section A-A;

FIG. 4 is a top perspective view of area 4 thereof;

FIG. 5 is a top perspective view of area 5 thereof;

FIG. 6 is a top view in plan thereof;

FIG. 7 is a bottom view in plan thereof;

FIG. 8 is a first end view (heel) in elevation thereof;

FIG. 9 is a second end view (toe) in elevation thereof;

FIG. 10 is a right side view in elevation thereof; and,

FIG. 11 is a left side view in elevation thereof.

The broken lines showing spikes form no part of the claimed design.

1 Claim, 7 Drawing Sheets
